UNITED STATES PATENT OFFICE.

EDWARD LLOYD PEASE, OF DARLINGTON, ENGLAND.

APPARATUS FOR THE SUBDIVISION AND TREATMENT OF FLUIDS.

Application filed February 1, 1921. Serial No. 441,706.

(GRANTED UNDER THE PROVISIONS OF THE ACT OF MARCH 3, 1921, 41 STAT. L., 1313.)

To all whom it may concern:

Be it known that I, EDWARD LLOYD PEASE, a subject of the King of Great Britain and Ireland, residing at Darlington, in the county of Durham, England, have invented Improvements in Apparatus for the Subdivision and Treatment of Fluids, of which the following is a specification.

This invention has reference to apparatus for the treatment of fluid of various kinds, including streams of finely divided or comminuted matter, such for example as coal or other dust, which, when mixed with a fluid carrier, for example air or other gas or gases or vapour, constitutes, in effect, a stream of fluid and is consequently hereinafter included in the term fluid.

The object of the present invention is to provide improved apparatus for the purpose referred to characterized by a number of plates or sheets (hereinafter referred to as sheets) having entirely flat or plane surfaces arranged close together so that they make contact with each other at certain regions and are so shaped that when assembled they provide narrow fluid mixing spaces that are in communication with one another by way of a passage or passages extending transversely through the set of sheets.

The apparatus is thus distinguished from other apparatus of a similar kind in this, that narrow spaces are obtainable equal in thickness to the thickness of the sheets employed, the number of such spaces, for a given length of apparatus, being determined only by the thickness of the sheets employed. Apparatus embodying the invention can be constructed in various forms depending to some extent upon the end to be attained, as

will be apparent from the examples now about to be described with the aid of the accompanying drawings, wherein Fig. 1 is a transverse section on the line I—I of Fig. 2 and Fig. 2 is a longitudinal section on the line II—II of Fig. 1, of one construction of apparatus that may advantageously be used for mixing fluid and for the interchange of heat between fluids. Fig. 3 shows in plan, a few of the sheets with the tubes shown in Figs. 1 and 2. Fig. 4 is a face view of the juxtaposed sheets used in a modified construction of the apparatus shown in Figs. 1, 2 and 3 and Fig. 5 is a longitudinal section corresponding to the

line V—V of Fig. 4. Fig. 6 is a horizontal section on the line VI—VI of Fig. 7, and Figs. 7 and 8 vertical sections on the lines VII—VII and VIII—VIII respectively of Fig. 6, showing a construction of the apparatus suitable for use as a gas and air mixing device or burner.

According to the arrangement shown in Figs. 1, 2 and 3, two sets of flat sheets A and B are employed bearing one against the other for part of their surface area and so shaped and arranged as shown, that when assembled together, flat shallow spaces *a* are left between the A set of sheets whilst similar spaces *b* are left between the B set of sheets, a transverse passage or space, indicated at *c* (Figs. 1 and 2), being left between adjacent edge portions of the sheets common to all the flat narrow spaces *a* and *b*. The passage or space *c* may be of any desired shape in cross section being shown in the example as of elongated shape. The arrangement is such that assuming the two sets of sheets to be fitted within a casing *d* or other structure having separate inlets *e* and *f* for fluids, the stream of fluid entering by one inlet, say *e*, will pass through the shallow spaces *a* between the A set of sheets and be subdivided into a number of thin flat streams of fluid, whilst the fluid entering by the other inlet *f* will pass through the shallow spaces *b* between the B set of sheets and be similarly subdivided into a number of thin flat streams, the two sets of streams intermingling in the common passage or space *c* through which the mixture of fluids will pass either under pressure or suction, and escape through an outlet *g* at one end of the apparatus.

The two sets of sheets A and B are shown as of equal thickness but they may obviously be of different gauges so that the spaces between the sheets of one set, for instance for air, may be of greater thickness than the spaces between the sheets of the other set designed for the passage of another gas.

An arrangement of adjacent and overlapping metal sheets such as just described, may advantageously be used for the interchange of heat between fluids. For this purpose, the two sets A and B of metal sheets formed with juxtaposed holes at parts thereof that bear directly against one another, may be traversed by one or more

tubes h , two are shown, fixed to the sheets and through which one of the fluids passes whilst another fluid passes through the spaces a and b left between adjacent sheets 5 which are arranged within a suitable casing d or other structure. Thus, air to be heated or cooled may be caused to flow through the spaces a and b and steam or cold water through the tube or tubes h , the surfaces of 10 the sheets affording a very large heating or cooling surface and the heated or cooled fluid passing between the sheets, escaping through the exit space or passage c common to them. Or steam from an engine or other 15 source may be caused to pass through the spaces a and b between the sheets A and B and a cooling liquid, such as water, through the tube or tubes h , or vice versa, the arrangement then forming a condenser. The 20 tube h , or each tube, passes through and is fixed, as by an expanding tool, in portions of the adjacent sheets that are, as hereinbefore stated, in direct surface contact with each other. This is a feature of considerable 25 importance as practically the whole external area of the tube is in direct contact with and completely covered by the edge portions of the holes in the sheets, whereby a very efficient transfer of heat from the tube to 30 the sheets is ensured. For heat interchanging purposes, it is important that the surface area of the metal in contact with the fluids should be large relatively to the volume of fluids used. For this purpose it is preferred 35 to use relatively small tubes and a large number of thin metal sheets in direct metallic edge contact therewith, thereby securing the high subdivision of the fluids required for the efficient interchanging of heat, or the 40 intermingling of fluids, and efficient transfer of heat.

In some cases, instead of using one or more tubes h with metal sheets A and B for purposes such as mentioned, and as 45 shown in Figs. 1, 2 and 3, the sets of metal sheets, at parts thereof where they are firmly held in direct surface contact with each other, may be formed with registering holes to form one or more passages for fluid, instead of fitting the holes with tubes.

Figs. 4 and 5 show an arrangement of this kind where the alternate plates A and B are formed with juxtaposed holes i adapted to form passages h' for fluid other than that flowing through the spaces a and b between the adjacent plates. By cutting away a portion of each plate adjacent to each hole i therein, as indicated at i' each passage will, in effect, form a tube having a series of perforations namely i' through which a fluid, admitted to each passage h' , can flow into the spaces a and b between the plates A and B and become mixed with another fluid or other fluids flowing through such spaces. 60 65 70 75 80 85 90 95 100 105 110 115 120 125 130

tubes h , two are shown, fixed to the sheets and through which one of the fluids passes whilst another fluid passes through the spaces a and b left between adjacent sheets 5 which are arranged within a suitable casing d or other structure. Thus, air to be heated or cooled may be caused to flow through the spaces a and b and steam or cold water through the tube or tubes h , the surfaces of 10 the sheets affording a very large heating or cooling surface and the heated or cooled fluid passing between the sheets, escaping through the exit space or passage c common to them. Or steam from an engine or other 15 source may be caused to pass through the spaces a and b between the sheets A and B and a cooling liquid, such as water, through the tube or tubes h , or vice versa, the arrangement then forming a condenser. The 20 tube h , or each tube, passes through and is fixed, as by an expanding tool, in portions of the adjacent sheets that are, as hereinbefore stated, in direct surface contact with each other. This is a feature of considerable 25 importance as practically the whole external area of the tube is in direct contact with and completely covered by the edge portions of the holes in the sheets, whereby a very efficient transfer of heat from the tube to 30 the sheets is ensured. For heat interchanging purposes, it is important that the surface area of the metal in contact with the fluids should be large relatively to the volume of fluids used. For this purpose it is preferred 35 to use relatively small tubes and a large number of thin metal sheets in direct metallic edge contact therewith, thereby securing the high subdivision of the fluids required for the efficient interchanging of heat, or the 40 intermingling of fluids, and efficient transfer of heat.

In the arrangement shown in Figs. 6, 7 and 8 two sets of sheets A' and B' are clamped together as by rivets h or bolts, and adapted to fit within a cylindrical casing d' provided with separate air end combustible 70 gas inlets n and o and within which the combined sheets can be mounted to be rotated, as by a spindle p and hand wheel r . For this purpose the spindle is connected to the two sets of sheets A' , B' through a collar p' and plate p^2 fixed to the spindle and to the lower end of the sets of sheets. The sets of sheets A' and B' are so relatively 80 shaped, as shown, that in one position there is a segmental set of shallow spaces a' between the sheets A' opposite the air inlet n and a segmental set of spaces b' between the sheets B' opposite the gas inlet o , a central exit space c^2 of circular section, or it may be 85 of other section, being left between the adjacent edges of the sheets. The remaining oppositely disposed segments of the two sets of sheets are held in close contact with each other, as by the rivets h , and can, by suitably turning the combined sheets about the central axis of the arrangement, be brought 90 into a position to close the air and gas inlets n and o . Such an arrangement may be used as an air and gas mixing valve or 95 burner. The entrance to the central space 100 c^2 , formed by the spaces a' , b' between the sheets can be largely varied in different sheets in a series. In the example shown in Fig. 6 they are of angular shape.

What I claim is:

1. Apparatus for purposes such as herein referred to, comprising a number of sheets having entirely flat or plane parallel surfaces arranged closely together and so shaped that they make contact with each other at certain regions thereof and form narrow spaces between those portions of alternate sheets that are not in contact with intermediate sheets and a passage which extends through the assembled sheets, at right angles to the plane thereof, and is in communication with the said narrow spaces.

2. Apparatus of the kind referred to, comprising a structure having openings therein for inlet and outlet of fluid, a number of sheets having entirely flat or plane parallel surfaces arranged closely together and so shaped that they make contact with each other at certain regions thereof and form narrow spaces between those portions

of alternate sheets that are not in contact with intermediate sheets and a passage which extends through the assembled sheets in a direction at right angles to the plane 5 thereof and is in communication with the said narrow spaces, the said spaces being in communication with some of the openings in the casing and the passage being in communication with a separate opening in the 10 casing.

3. Apparatus of the kind described, comprising sheets having entirely flat or plane surfaces arranged closely together so that they make regional contact with each other 15 leaving narrow fluid spaces between them, each sheet being notched and the several sheets being arranged so that the notch in one sheet overlaps the notch in an adjacent sheet thereby forming a passage that extends transversely through all the sheets and is in communication with the narrow fluid spaces aforesaid, substantially as described. 20

4. Apparatus of the kind described, comprising a structure having inlets for fluid 25 and an outlet for fluid, two sets of notched overlapping sheets having entirely flat or plane surfaces arranged close together within said structure so that they make regional contact with each other over part of their area and form two sets of narrow fluid 30

spaces between the said sheets in communication with the respective inlets and a passage that extends transversely through all the sheets and is in communication with the several narrow spaces and with the said outlet, substantially as described. 35

5. Apparatus of the kind described, comprising a structure having inlets for fluid and an outlet for fluid, two sets of notched overlapping sheets having entirely flat or plane surfaces arranged close together within said structure so that they make regional contact with each other over part of their area and form two sets of narrow fluid 40 spaces between the said sheets in communication with the respective inlets and a passage that communicates with the several narrow spaces and with the said outlet, said sheets being also pierced in different regions that are in contact with one another, the 45 piercings being juxtaposed to form a separate passageway that extends through the juxtaposed regional portions, substantially as described, a portion of each sheet being cut away so as to form a plurality of passages from said passageway to each of the 50 fluid spaces. 55

Signed at London, England, this fourteenth day of January, 1921.

EDWARD LLOYD PEASE.
